UNITED STATES PATENT OFFICE.

WILLIAM DANIEL DOONAN, OF BUTTE, MONTANA.

TOOL FOR BENDING SPRINGS.

1,417,890.

Specification of Letters Patent. Patented May 30, 1922.

Application filed December 9, 1921. Serial No. 521,152.

To all whom it may concern:

Be it known that I, WILLIAM D. DOONAN, a citizen of the United States, residing at Butte, in the county of Silverbow and State 5 of Montana, have invented certain new and useful Improvements in Tools for Bending Springs, of which the following is a specification.

This invention relates to tools for bending metal, and more particularly to hand operated tools for bending curved leaf springs; and it consists in the novel construction and combination of the parts hereinafter fully described and claimed, whereby the leaf 10 springs of motors cars which have deteriorated by use are re-set and restored to their original strength and elasticity without injury to the original temper of the 15 springs.

20 In the drawings, Figure 1 is a front view of a tool for bending springs constructed according to this invention. Fig. 2 is a side view of the same. Fig. 3 is an end view of the jaws.

25 Two levers 5 and 6 are provided, and are pivoted by pins 7 to the end portions of two links 8 which straddle their middle portions. The free end portion 9 of the lever 5 is longer than the free end portion of 30 the lever 6 and forms one bending jaw of the tool. The lever 6 has a projection 10 on its free end portion which forms a shoulder 12, and a block 14 is secured on this projection 10 against the shoulder 12. The 35 projection 10 is preferably rectangular to prevent the block from turning, and its end 15 is riveted over to hold the block securely in place.

The block 14 has a concave face 16 arranged opposite the jaw 9, and projecting laterally on each side of it. The block 14 forms the other jaw, and the leaf spring is set up by pressure between these two jaws. A portion of the leaf spring 13 is shown in 45 dotted lines. The spring is heated slightly, but not sufficiently to draw its original temper, and it is found that springs can be successively re-bent and set up in this manner, provided the jaws are accurately set with 50 relation to each other so as not to bend the spring too much and thereby strain it.

The levers 5 and 6 are operated by means

of two long handles 20 and 21, which are pivoted together at one end by a pin 22, and which have stops 24 at their middle parts 55 which limit their movement toward each other.

Adjusting links 25 and 26 are provided, and are pivoted at one end by pins 27 to the handles between the pivot 22 and the stops. 60 The links are pivoted at the other end to the end portions of the levers 5 and 6 by pins 28. Set-screws 30 are screwed into holes in the adjusting links adjacent to the pins 28, and their ends bear against the outer 65 sides of the handles. When the screws 30 are screwed up a little they increase the normal distance between the two pins 28, so that the bending jaws are moved closer together. 70

The bending jaws are accurately set by means of the set-screws so that the leaf spring is bent to the maximum extent desired when the stops 24 on the handles come together. The handles are relatively very 75 long so that the leverage is very great, and so that the heated springs can be re-bent and set up by hand power without injury to them.

What I claim is:

1. A bending tool, comprising two pivoted levers one of which has a straight longitudinal end portion which forms one bending jaw, and a block arranged crosswise of the said jaw and secured to the corresponding 85 end portion of the other lever and provided with a concave bending surface which projects laterally on each side of the said jaw.

2. A bending tool, comprising two levers one of which has a straight longitudinal end portion which forms one bending jaw, links arranged crosswise of the middle parts of the said levers and having their end portions pivoted to them, and a block arranged crosswise of the said jaw and secured to the 95 corresponding end portion of the other lever and provided with a concave bending surface which projects laterally on each side of the said jaw.

3. A bending tool, comprising two pivoted levers one of which has a straight longitudinal end portion which forms one bending jaw, and a block arranged crosswise of the said jaw and secured to the corresponding 100

end portion of the other lever and provided with a concave bending surface which projects laterally on each side of the said jaw, in combination with two handles pivoted together at one end and provided with a stop device, adjusting links pivoted at one end to the said handles and at the other end to the

said levers, and means for setting the adjusting links laterally with respect to the handles.

In testimony whereof I have affixed my signature.

WILLIAM DANIEL DOONAN.
